(57) **CLAIM**

The ornamental design for a display mount with decorative lighting, as shown and described.

DESCRIPTION

FIG. 1 is a front, top, left side perspective view of a display mount with decorative lighting showing my new design; FIG. 2 is a back, top, right side perspective view thereof; FIG. 3 is a front view thereof; FIG. 4 is a back view thereof; FIG. 5 is a left side view thereof; FIG. 6 is a right side view thereof; FIG. 7 is a top view thereof; and, FIG. 8 is a bottom view thereof. Broken lines are used to illustrate features of the display mount with decorative lighting that form no part of the claimed design.
